1

This invention relates to devices for accelerating charged particles such as electrons to high velocity and hence high potential by means of magnetic induction effects. These devices which are often referred to as betatrons or ray transformers include generally an evacuated toroidal tube into which streams of electrons are periodically introduced for acceleration, and a magnetic field system varying with time that has a direction transverse to the plane of the tube and electron motion.

The magnetic field affects the electron stream in two ways. Firstly, since the field has a direction transverse to the plane of motion of the electron stream, it tends to hold the electrons and cause them to follow a stabilized and generally circular orbit. In the second place, the time-varying magnetic flux enclosed by the orbit of any particular electron necessarily produces an electric field which tends to accelerate that particular electron along the orbit. During one cycle of operation, which will be explained in detail hereinafter, an incoming electron stream may be constantly accelerated for as many as several hundred thousand turns around the orbit and therefore reaches enormously high velocity and voltage, at which time the stream can be diverted from the orbit to produce useful results such as for example to bombard a target anode to create X-rays.

It has already been definitely established that the radius of the orbit in the tube along which the electron stream will be stabilized for acceleration will depend upon the distribution of the time-varying magnetic field with respect to the tube and such relationship may be expressed mathematically by the equation

$$\phi = 2\pi r^2 H, \quad (1)$$

where

ϕ is the flux included within the electron orbit, r is the radius of the electron orbit, and H is the magnetic field strength at the orbit.

It thus follows from this equation that electron stabilization will occur along an orbit at a radius r where the total flux within the orbit is twice that which would be produced by a homogeneous magnetic field having an average intensity equal to the field intensity at the orbit extending over the entire area enclosed by the orbit.

Using the above equation as a fundamental basis for engineering design data, it has proven practical to build a magnetic structure and to so locate the toroidal tube with respect to the magnetic field produced by the structure that the

equilibrium orbit along which electron acceleration is to take place will lie at any desired radial position in the tube, which is usually at the geometrical center. Suitable locations for the electron producing means and the target anode or exit point are then selected either radially inward of, or outward from, the acceleration orbit so that these elements will be entirely clear of any possible interference with the electron stream as it travels round and round in the tube along its orbit.

Once the electron stream produced by the electron gun has reached the equilibrium orbit of the particular radius for which the apparatus has been designed, no appreciable difficulties have been encountered in maintaining the stream on the orbit inasmuch as the magnetic structure is usually so designed that the strength of the magnetic field in the vicinity of the tube decreases radially outwardly at such a rate as to give rise to stabilizing forces which oppose any tendency on the part of the electrons to leave the main stream. Magnetic or electrostatic lens may also be used to augment stabilization of the electron stream at the acceleration orbit.

However, considerable difficulty has been experienced in the past in introducing the electron streams into the tube in such manner that the streams will be assured of reaching the acceleration orbit without impinging upon the walls of the tube or upon the electron producing means or the target anode assuming the device to be constructed with these elements located within the interior of the toroidal tube. If the electron streams are introduced into the tube from a point radially outward of the acceleration orbit, the time-varying magnetic field under which the stream is then accelerated does have some effect upon the stream to cause it to move along a spiral path of diminishing radius and gradually approach the acceleration orbit. However, under normal conditions, using frequencies of about 50 cycles per second for the magnetic field, the forces acting upon the electron stream for driving the latter radially inward to merge with the acceleration orbit are, however, so small that only a relatively minor portion of the total content of the electron stream may actually reach the orbit, the remainder being lost by impingement either upon the walls of the tube or upon the electron producing or target electrodes.

When the apparatus is constructed in such manner that the electron gun and/or target anode or place of exit for the electron stream are located outside of the bounds of the toroidal tube such as for example in arm portions which may

be arranged tangentially of the tube, the problem of introducing the electron stream to the acceleration orbit is obviously made all the more difficult because of the increased radial distance between the entrance path and the acceleration orbit of the apparatus.

The general object of this invention is therefore to provide an improved arrangement for introducing the electron stream into the acceleration orbit of an electron accelerator. Another object is to provide in an induction type electron accelerator for stabilizing or guiding an injected electron stream along a spiral path into the acceleration orbit.

Another object is to provide for leading an electron stream into the acceleration orbit of an induction type electron accelerator along a spiral path, the guide path being established by a force acting radially on the entering electron stream and which diminishes rapidly with time following electron injection. Another object is to provide for guiding an electron stream of an electron accelerator into the acceleration orbit by means of a radially acting electrostatic field. Still another object is to provide a stabilized spiral entrance path for the entering electron stream of an induction type accelerator, the guide force being derived by disturbing the normal radial gradient of the time varied magnetic field. Another object is to provide for guiding an electron stream into a stabilized orbit for acceleration and for thereafter guiding the stream away from the orbit when the stream has reached the desired final velocity, the guiding means being produced by a radially acting force which is first applied when the stream is injected and subsequently reapplied when the stream reaches its final velocity. Yet another object is to provide for guiding an electron stream of an induction type electron accelerator by means of an auxiliary magnetic field which is superimposed upon the normal guiding force component of the main magnetic field, the auxiliary force serving first to guide the injected electron stream into the circular path along which its acceleration is to take place and also to thereafter guide the stream away from such path when the stream has attained the desired velocity.

A more specific object of the invention is to provide an auxiliary field producing device by which an electron stream when first introduced into an induction type electron accelerator is made to follow a contracting spiral path to carry the stream into the acceleration orbit, the path being thereafter expanded spirally by the same device when the electron stream has attained its final velocity to lead the stream outwardly from the orbit. Another specific object is to provide a stabilized spiral introduction path for the injected electron stream, the path being produced by a radially directed and rapidly decreasing electrostatic field that encloses a substantial portion of the circular path. Yet another specific object is to provide for guiding an injected electron stream along a stabilized and rapidly diminishing spiral path into ultimate coincidence with the acceleration orbit by means of an auxiliary magnetic field which is superimposed upon the normal magnetic field employed for electron acceleration. Yet another object is to provide for guiding the electron stream along a path which is tangent to the spiral path by which the stream is thereafter guided into or away from the acceleration orbit.

These and other objects and advantages to be

derived from the invention will become apparent from the following detailed description and from the accompanying drawings which illustrate several different constructional examples by which the desired improved results according to the invention may be attained.

In the drawings, Fig. 1 is a vertical central section through one constructional form of the invention; Fig. 2 is a horizontal section taken on lines 2-2 of Fig. 1 drawn to a somewhat enlarged scale, only the toroidal tube being shown; Fig. 3 is a substantially half vertical section showing a modified electrode arrangement for the Fig. 1 construction by which the auxiliary electrical field can be produced; Figs. 4 and 6 are also vertical central sections which illustrate other constructional forms of the invention; Fig. 5 is a diagram showing the control circuit used for the Fig. 4 construction; Fig. 7 is a somewhat diagrammatic view showing still another form of the invention; and Fig. 8 is a diagram showing the control circuit used for the construction shown in Figs. 1 and 2.

Referring now to the drawings, the induction accelerator shown in Fig. 1 comprises a magnetic field structure 10 made up from vertically disposed steel laminations of appropriate contour which includes a pair of cylindrical pole pieces 11-11' separated by air gap 12 and located concentrically along axis a-a, and a pair of annular poles 13-13' facing each other and separated by air gap 14. Yoke members 15 complete the magnetic circuit for the time-varying magnetic flux set up in the annular and cylindrical poles. Poles 11-11' and 13-13' are surrounded by an annular winding preferably split into two coil sections 16-16' wound in the same relative direction and connected in series for energization from an alternating current source 17 of suitable frequency which for example may be an alternator running at 50 cycles/sec. An annular evacuated envelope 18, preferably glass, rests in the air gap 14 between the annular poles 13-13'. By means of an electrical control circuit to be later described in more detail, electron streams are injected periodically into the tube 18 from an electron producing device 20 that is preferably located in an arm portion 18a of tube 18 arranged tangentially of the tube. Another tangentially arranged arm portion 18b of tube 18 is provided for example with a target anode 23 against which the electrons are caused to impinge to give off X-rays after the electrons have attained their final velocity. Once the injected electrons have reached the acceleration orbit K, the magnetic field varying with time in poles 11-11' and 13-13' causes the electrons to be constantly accelerated round and round the tube along the orbit.

As previously explained, one of the principal difficulties encountered in the operation of these devices is properly guiding the electron stream from the electron producer 20 into the stabilized acceleration orbit K without loss, and in accordance with this invention, a most satisfactory guide path for the electron stream is established by applying an auxiliary and radially directed guiding force to the entering electron stream to augment the guiding or stabilizing force normally derived from the main magnetic field that produces acceleration of the electrons.

In the embodiment of the invention shown in Figs. 1 and 2, the auxiliary radially acting force for guiding the incoming electron stream is created by a radially directed electrostatic field set

up between two sets of curved plates 24-24' and 25-25' located within the tube 18 and which together extend almost completely around the tube. The plates of each set are spaced parallel with and lie on opposite sides of the acceleration orbit K, and the plates extend in a direction parallel with the axis a-a of the magnetic induction apparatus. The electrostatic field produced between the plates of each set when charged thus extends in a direction radially of axis a-a.

In the illustrated construction of the magnetic induction apparatus in which the electron stream is introduced into tube 18 from a point radially outward from the acceleration orbit K, the auxiliary force to be applied to the incoming stream of electrons must of course be such as to guide the stream radially inward. The two sets of plates 24-24' and 25-25' are accordingly so charged that the potential of the outer plates 24 and 25 is positive with respect to the potential on the inner plates 24' and 25'. The plates are charged prior to injection of the electron stream through a control circuit (Fig. 8) operating in timed relation with electron injection and the electrostatic field between the plates has its maximum strength at the time that the electron stream enters the tube. The electrostatic field is thereupon discharged by short-circuiting the plates through an impedance and the net effect of this diminishing electrostatic field on the stream is to thus guide it radially inward along a spiral curve of decreasing radius and meet the acceleration orbit K.

A typical spiral path traveled by an incoming electron stream is shown in Fig. 2 wherein the stream entering the tube along path a is moved radially inward after only one turn around the tube to path b that is spaced well inside of the initial path a. By choice of the time constant of the discharge of the electrostatic field between the two sets of plates 24-24' and 25-25', it becomes possible to adjust the radial spacing of the sections a and b of the spiral curve so that even with a substantially high injection velocity of the electron stream, the latter may be guided safely into the acceleration orbit K without danger of electron loss by impingement upon the surfaces of the plates. The time constant may, for example, be of the order of 1 to 10 μ sec.

As an additional guiding force for the electron stream to enable it to reach the tube space between the arcuate condenser electrodes 24-24' and 25-25', another pair of electrodes 26-26' are provided immediately in front of the electron producer 20. These latter electrodes are charged to a constant positive voltage and the electrostatic field set up between them guides the injected electrons along a path which is substantially tangential to the spiral path later traveled by the electrons.

In order to deflect the electrons from the circular path after their acceleration has been completed, the second set of arcuate plates 25-25' is recharged at the proper instant to their original polarity to reestablish the electrostatic field. Hence, the electron stream will spiral outwardly from the acceleration orbit K at a rate determined by the rise in potential across the plates 25-25', and ultimately pass through another auxiliary guiding electric field established between positively charged plates 27-27' and impinge upon target anode 23.

The foregoing arrangement for deflecting the electron stream outwardly is however unsatisfactory to the extent that the electrons that are

located between the deflecting plates at the moment of switching-in of the electrostatic field will describe a curved path different from the path of the electrons that are located outside the deflecting field at that moment and which are yet to pass between these plates. In order to keep the number of electrons traveling the first mentioned curved path as small as possible and to make them unimportant in the operation 10 of the ray transformer, the field for leading the stream away from orbit K, according to the invention, preferably takes up only a small part of the whole circumference of the circular path, about $\frac{1}{5}$ or $\frac{1}{10}$ or even less. The portion of the 15 electrons from the entire charge of the tube that follows a curved path different from that of the other electrons is then correspondingly small and amounts only to $\frac{1}{5}$ or $\frac{1}{10}$ or even less of the entire charge.

20 The set of deflecting plates 25-25' is accordingly made as short in the direction of travel (clockwise) of the electrons as is possible taking into consideration the necessary deflecting forces and the strength of the deflecting field to be produced. In order that in this connection, the greatest possible effect of the deflecting field shall be obtained, the deflecting plates are arranged, according to a further feature of the invention, as far from the place of issuance of the electrons (or in front of the place where the deflected electrons are needed) as will give the greatest deflection. In the stabilizing field of force of the ray transformer, the electrons when deflected by a force transverse to the circular 30 path will describe transverse oscillations at right angles to the circular path as is well known. The greatest deflection is given therefore approximately at a distance of a $\frac{1}{4}$ wave length behind the center of the deflecting field. The 35 best place for the deflecting plates 25-25' is thus about $\frac{1}{4}$ wave length in advance of the place of issuance of the electrons.

The control circuit arrangement by which the two sets of plates 24-24' and 25-25' are initially 45 charged prior to the injection of the electron stream into the tube, and thereafter discharged to guide the stream radially inwardly to the acceleration orbit K, and the control by which plates 25-25' are recharged upon completion of 50 the acceleration phase of the stream to thereafter guide the latter outwardly from such orbit that is used in connection with another embodiment of the invention is shown in Fig. 8. In this diagram, 66 indicates a thyratron tube which 55 switches the deflecting voltage on to the electrodes 25, 25' when the rotating electrons have attained the desired voltage and have to be brought out of the toroidal tube or made to impinge upon the target anode 23 as shown in Fig. 2. The instant at which this occurs can be adjusted 60 by a phase shifter 72 which enables the phase of the thyratron grid voltage to be varied relative to the magnetic flux of the betatron. Thytratrons 68 and 69, whose grids 68a and 69a respectively are excited over an air-core transformer 43 by the anode voltage of the electron gun 20, discharge the deflecting plates 25, 25' and 24, 24' over resistances 70, 71 and at the moment the electrons are introduced, thus produce 65 the spiral curve already described for the path of the electrons brought into the toroidal tube 18 (Fig. 2).

Transformer 62 together with rectifier tube 63 and condenser 67 produces the direct voltage for 70 charging plates 24, 24' and 25, 25' over resistances

64 and 65, whilst the remaining elements shown in Fig. 8 have the same function as those described later on in connection with Fig. 5.

In accordance with a further feature of the invention, the plates between which the electrostatic field is formed may be so constructed that they yield also a force component in the direction of the axis that has a stabilizing effect, i. e. it exerts forces on the electrons directed everywhere on the plane of the circular path. In this way, the electron stream can be made smaller in the direction of the axis, this affording many advantages for the introduction and withdrawal of the electrons, such as small admission and discharge openings, smaller losses by dispersed electrons and lesser influence of disturbing fields, etc.

With a field directed inwards, the strength of field consequently must diminish radially outwards, while with a field directed outwards, the strength of field must increase in the radial direction. A modified construction showing the latter case is illustrated in Fig. 3, the center line of the stabilized circular acceleration path of the electrons in tube 18' being designated K, and the arcuate deflecting plates shown at 30, 31. A voltage forcing the electrons outward acts between the large inner plate 30 and the small outer plate 31, i. e. the forces acting on the electrons have a component directed everywhere on the plane of the circular path. If the strength of the field is to diminish outwards, the larger plate 30 must then be placed at the outside and the smaller plate 31 at the inside of the annular tube 18'.

In the event that it is desired to use electric or magnetic lenses for stabilizing the electron path, it may become impractical, because of spacial difficulties, to accommodate both the lenses and the electrostatic plates shown in Figs. 1-3 which provide for introducing the electrons along a diminishing spiral path into the acceleration orbit. If the use of electrode plates is not practical then in accordance with another constructional embodiment of the invention as shown in Fig. 4, the radially acting guiding force which is applied to the incoming electron stream may be derived by disturbing the normal radial gradient of the main magnetic field in such manner as to temporarily alter the normal ratio between the magnetic flux within the tube 18, i. e. the flux through the inducing field poles 11-11' and the intensity H_r of the flux at the orbit K between the control field poles 13-13'. Referring now to Fig. 4, the general construction of the induction accelerator is seen to be similar to that shown in Figs. 1 and 2. However in lieu of the electrodes 24-24' and 25-25', auxiliary field windings are provided at the inner and outer sides of the control poles 13-13'. One of these windings consisting of coil sections 32-32' is placed directly outside of the control poles 13-13', and the other winding consisting of coil sections 33-33' is placed directly inside of the control poles. The two windings are connected in series for energization in a circuit which will be explained hereafter in detail, the current through one of the windings being in a direction opposite to that in the other winding.

Assuming the electron accelerating device is constructed in a manner similar to that shown in Figs. 1 and 2, in which the electron stream is introduced into the tube from a point which lies radially outward from the orbit K along which acceleration of the stream is to take place,

it will be evident that the auxiliary magnetic field produced by windings 32-32' and 33-33' must oppose and hence weaken the normal magnetic control field across poles 13-13' which is produced by the windings 16-16' in order that the ratio of the control field with respect to the inducing field will be initially less than that at which the electron stream is stabilized at the radius of the orbit K. The effect of the change in ratio between the two components of the main magnetic field will be to enlarge the orbit of electron stabilization in the direction of the entrance path of the injected electron stream. As with the case of the electrostatic field produced by plates 24-24' and 25-25' of Fig. 1, the magnetic field produced by the auxiliary windings 32-32' and 33-33' must likewise diminish rapidly with time to zero so that the path of the injected electron stream is stabilized along a spiral orbit of decreasing radius as the normal gradient of the magnetic field is restored, the path ultimately merging with the acceleration orbit K when the field gradient has attained its normal characteristic.

It can be shown that the inducing path becomes a logarithmic decreasing spiral (i. e. the radius of the circular path changes according to the law $R=R_0+\Delta R e^{-t/T}$) when the auxiliary magnetic field changes according to the law:

$$B_{aux.} = B_{aux. max.} \cdot e^{-t/T} (1+at)$$

$$\sim B_{aux. max.} \cdot e^{-t/bT}$$

where T is the time constant of the introduction path, $e=2.783$, and a and b are constants that are dependent on special conditions (dimensions and frequency or the magnetic induction device).

Normally this time constant will be of the order of 1 to 10 μ sec., and since the windings by which the auxiliary magnetic field is produced may have large inductance (up to 1-2 millihenries) special consideration must be given to the design of the circuit for carrying out this switching operation fast enough. One suitable way for diminishing the auxiliary magnetic field with time would be to send a current through the auxiliary windings in the opposite direction and an arrangement for reducing the field in such manner will be presently described.

As with the construction shown in Fig. 1 and Fig. 8, the action of the auxiliary magnetic field must be timed with the injection of electrons into the tube 18 and energization of the windings 16-16' by which the magnetic inducing and control fields varying with time are produced. A suitable circuit is shown in Fig. 5.

Referring now to Fig. 5, it will be seen that a blind load condenser 38 is connected in parallel with the main windings 16-16' across the terminals of the alternating current source 17 and that a current transformer 39 which may preferably be of the highly saturated type has its primary winding connected in series with the main windings 16-16'. The electron emissive device 20 by which streams of electrons are periodically introduced into the tube 18 for acceleration is supplied with high voltage from a transformer 40 also connected to the alternating current source 17 by way of a grid controlled vacuum valve 41. The grid 41a of valve 41 is temporarily driven positive from an otherwise negative value sufficient to maintain the tube non-conductive by the voltage peak of the current transformer 39 whose secondary winding is connected between the cathode 41b and grid 41a of valve 41, and the resultant current flow in the anode-cathode cir-

cuit of valve 41 causes a stream of electrons to be produced at the electron emissive device 20. After a brief period, a glow tube 42 connected in parallel with the secondary of transformer 39 becomes conductive and short circuits the same. Negative cut-off bias to grid 41a is then re-established through grid battery 41c whereupon valve 41 is rendered non-conductive with the result that the production of electrons by the device 20 then ceases. Assuming the electron stream to be accelerated for a quarter of a cycle of the magnetic flux, operation of the electron producing device 20 is preferably timed with energization of the main magnetizing coils 16-16' in such manner that the stream of electrons is shot into the tube 18 at or near the instant at which the magnetic field produced by windings 16-16' passes through the zero point in the flux cycle.

During the quarter cycle preceding introduction of the electron stream into the tube 18, the auxiliary windings 32-32' and 33-33' are energized through a resistor 37 and a rectifier 36 that is rendered conductive during this portion of the cycle, and the magnetic field ϕ' produced by these auxiliary windings which threads across tube 18 through the control poles 13-13' opposes the main flux ϕ which is set up in these poles as a result of energization of the main windings 16-16'. Rectifier 36 may as shown in the circuit diagram be supplied by a section 60b of the secondary winding of transformer 60 whose primary 60a is also connected to the alternating current source 17. Hence at the instant that the stream of electrons is introduced into tube 18, a disturbing field produced by the auxiliary windings 32-32' and 33-33' is already present in the control poles 13-13' and, since this disturbing magnetic field is opposed to the field established through these poles by windings 16-16' the effect of the disturbing field is to decrease the normal ratio between the flux ϕ inside of orbit K and the field strength H_r at such orbit with the result that the incoming electron stream will be initially stabilized along its entrance path which lies radially outward of the acceleration orbit K. In order to gradually contract the entrance path of the electron stream inwardly along a spiral path which will finally merge with orbit K, the opposed magnetic field produced by auxiliary coils 32-32' and 33-33' is made to diminish with time to zero. In the present constructional embodiment of the invention, the opposing magnetic field is so reduced by sending a current through the coils in a direction opposite to that in which these coils are energized from rectifier 36, and such current is supplied to the coils by means of a circuit that includes a thyratron valve 34, resistor 44 and another section 60c of the secondary winding of transformer 60. Since the opposing field set up in the coils 32-32' and 33-33' is to diminish beginning with the instant that the stream of electrons is introduced into the tube, provisions are made for rendering the thyratron valve 34 conductive at such time and hence the grid 34a of thyratron 34 which controls its conductivity is preferably connected to the secondary of an air core transformer 43, the primary of which is connected in the anode-cathode circuit of valve 41 that controls the production of the electron stream. Thus as soon as valve 41 is rendered conductive to produce the electron stream, the accompanying voltage surge at the transformer 43 causes the grid 34a of thyratron 34 to swing to such potential that the thyratron

is rendered conductive and hence causes a rapidly increasing current to flow by way of resistor 44 through the auxiliary coils 32-32' and 33-33', the effect of which is to restore the original excitation of these windings and the opposing magnetic field produced thereby to zero. As the opposing magnetic field which was initially set up in these coils by way of rectifier 36 and resistor 37 is neutralized with time by the reverse current flow through them the ratio of the field strength H_r at the orbit K to the flux within the orbit increases with the result that the entering path taken by the electron stream will be correspondingly decreased in a radial direction along a spiral path and finally coincides with the acceleration orbit K when the opposing magnetic effect set up by the auxiliary coils 32-32' and 33-33' has been reduced to zero.

As the magnetic field produced by the main windings 16-16' increases from zero with time, the electron stream introduced into the tube along the radially inwardly directed spiral path will be accelerated along orbit K. After the stream has been accelerated to the desired velocity, which in the constructional embodiment shown will reach a maximum when the flux ϕ produced by the main windings 16-16' reaches its maximum, the auxiliary coils 32-32', 33-33' are again energized in the same direction as they were energized from the rectifier 36 to thereby again set up an auxiliary and opposing magnetic flux through the control poles 13-13' that once again disturbs the normal ratio between the flux ϕ within the orbit K and the field strength H_r at the orbit. Hence the stabilization orbit of the electron stream is now expanded radially outward from the acceleration orbit K to thereby guide the electron stream in a stabilized manner along a spiral path to the positively charged deflecting plates 27-27' provided at the outlet arm 18b of tube 18.

The current for reenergizing the auxiliary coils 32-32', 33-33' at the termination of the acceleration period may be obtained by means of another control circuit which includes rectifier 49, resistance 50, another thyratron tube 35 and condenser 46. The instant at which the control grid 35a of thyratron 35 renders the latter conductive is controlled through a transformer coupling 45, the condenser 47 and an adjustable resistor 48. Rectifier 49 is rendered conductive during the period in which the electron stream is being accelerated in the tube and charges condenser 46 through the resistor 61. Thus when the acceleration of the electron stream is approaching completion and thyratron 35 is rendered conductive, condenser 46 is discharged through the auxiliary coils 32-32' and 33-33' which results in an expansion of the electron orbit.

Following the discharge of the electron stream from tube 18, the opposing magnetic field set up in coils 32-32' and 33-33' by the discharge of condenser 46 will disappear and the whole electron acceleration device will then remain inoperative for approximately that half of the flux cycle in which the flux changes between its maximum positive and negative values. Thereupon the rectifier 36 will again be rendered conductive and the auxiliary coils 32-32' and 33-33' re-energized in advance of the introduction of the next following electron stream to be introduced into the tube 18 as the electron producing device 20 is once again energized.

As may be seen from the Fig. 5 circuit, the time

constant T_1 for the disappearance of the auxiliary opposing magnetic field is determined by resistance 44 and the inductance L of the auxiliary coils 32-32' and 33-33' i. e.

$$T_1 = \frac{L}{R_{44}}$$

while the time constant T_2 for the rise of the auxiliary magnetic field used for ejection of the electrons from the acceleration orbit K will be determined by the resistance 50, i. e.

$$T_2 = \frac{L}{R_{50}}$$

While the circuit shown in Fig. 5 is to be preferred, it is to be understood that it may be varied without departing from the invention.

In Fig. 6 there is shown an application of the invention to still another type of magnetic induction device for accelerating electrons. Referring now to Fig. 6, the magnetic structure of the device is seen to be similar to those shown in Figs. 1 and 4 except that the central core 51 is unbroken as distinguished from the pole pieces 11-11' and gap 12 of the other constructions. With this type of construction as more completely explained in my co-pending application Serial No. 715,933, filed December 13, 1946, the correct ratio between the inducing field and the control field is obtained by a winding 52 that encircles the central core 51 and which is connected in parallel with the main windings 16-16'. Associated with winding 52 is a transformer 53, the secondary 53b of which is connected in series with winding 52. The primary winding 53a is adapted to be energized prior to the introduction of the electron stream into the tube 18 by a control circuit similar to the one shown in Fig. 5 for effecting energization of the auxiliary coils 32-32' and 33-33' of the Fig. 4 embodiment of the invention. The resulting voltage induced in the transformer secondary 53b causes an auxiliary magnetic flux to be set up in the magnetic structure of the induction accelerator prior to the injection of the electron stream which disturbs the normal relationship between the inducing flux ϕ through the orbit K and the field strength H_r at the orbit. The disturbance has the same effect as in the other constructions and causes the normal control field to weaken with respect to the inducing field and establish an initial stabilization path for the incoming electron stream at a location radially outward from the acceleration orbit K. At the instant when the electron stream is shot into the tube, voltage of opposite polarity is applied to the primary winding 53a and the corresponding voltage induced in the secondary winding 53b then serves to neutralize the effect of the auxiliary flux previously set up by this winding. As with the other embodiments of the invention, the disturbing auxiliary flux diminishes rapidly with time from the instant of electron injection and hence causes the electron stream to spiral inwardly from the introduction path to the acceleration orbit K.

The invention may also be applied to the type of magnetic induction accelerator where the control poles of the device are pre-magnetized with direct current as more fully explained in my co-pending application Ser. No. 708,552, filed November 8, 1946. This type of device which has been illustrated in Fig. 7 somewhat diagrammatically is structurally similar to the device shown in Fig. 6 having an uninterrupted cen-

tral core surrounded by a winding 54 corresponding to winding 52 of Fig. 6 energized in opposition to the main windings 16-16', and a direct current winding 55 on the control poles that produces a premagnetizing unidirectional component of flux in the control pulse. The alternating current that is induced in the direct current premagnetizing winding 55 by the alternating component of the flux in the control poles must be compensated for in order that no alternating current shall flow in the direct current premagnetizing circuit. In the illustrated embodiment of the invention, the compensation is effected through the use of a transformer 56 having its secondary winding 56a connected in series with the premagnetizing winding 55 and its primary 56b connected in parallel with the main field windings 16-16' across the alternating current source 17. With this type of induction accelerator, the auxiliary magnetic field which is superimposed upon the control field through poles 13-13' to establish the spiral guiding path for the incoming electron stream may be set up by means of an additional winding around the control poles but a preferred and more simple arrangement is to establish the auxiliary guiding field in the direct current winding 55 itself. One suitable arrangement as shown in Fig. 7 is to provide the compensation transformer 56 with an additional primary winding 56c. As with the other embodiments of the invention, the voltage applied at terminals 57 to this additional primary winding 56c would be so phased in the operating cycle of the induction accelerator that the auxiliary and opposing flux set up by it in the control poles 13-13' would be established prior to injection of the stream of electrons, the flux thereafter being diminished with time. Also, as in the other embodiments of the invention, winding 56c may also be reenergized at the conclusion of the accelerating phase to lead the electron stream spirally away from the acceleration orbit.

In the event that it is desired to apply the invention to a pair of magnetic induction devices of the pre-magnetized type working together, as also described in my application Ser. No. 708,552, the direct current windings can be connected in series and the compensation transformer omitted. The additional current necessary for spiral guiding of the electrons can be induced with the aid of a special transformer in the direct current circuit. Due to the direct current pre-magnetizing, this additional transformer must likewise be provided with a suitable air gap.

In conclusion, it is to be understood that while in accordance with the patent statutes I have illustrated preferred constructional embodiments of the invention, the principles underlying the invention may be applied to types of electron accelerators in which the electron producing means and/or the target anode are located within the toroidal tube itself rather than in arm portions arranged tangentially thereto as illustrated. Furthermore, it will be evident that should the electron producing means be located radially inward from the acceleration orbit K, thus requiring an initial expansion of the entering orbit of the stream to reach the normal accelerating orbit, the auxiliary disturbing field decreasing with time which is superimposed upon the flux threading the toroidal tube across the control poles would be such as to aid the flux through the control poles rather than op-

pose it. If, in the latter construction, the target anode or place of exit for the accelerated electron stream is located radially outward from the acceleration orbit K, the auxiliary disturbing field to be produced at the instant of electron ejection from the orbit K would be such as to oppose the field through the control poles, as described in the illustrated embodiments of the invention. Conversely, should the electron producing means be located radially outward from the orbit along which the stream of electrons is to be stabilized for the acceleration phase and the target anode or exit point be located radially inward from the acceleration orbit, it then follows that the auxiliary field should first oppose the control field in order to stabilize the incoming electron stream along a spiral path of decreasing radius to guide it into the acceleration orbit, and to then augment the effect of the control field with respect to the inducing field when the stream has attained its ejection velocity in order to stabilize the electron stream along a spiral path further decreasing in radius so as to impinge upon the target anode.

For similar reasons, the polarity of the electrostatic field produced by the electrodes 24-24' and 25-25' in the Fig. 1 embodiment will of course depend upon the relative radial disposition of the target anode and also the entering place of the electron stream with respect to the acceleration orbit.

I claim:

1. The combination with an electron accelerator of the type wherein the electrons are caused to be accelerated along a stabilized orbit and wherein electrons are injected into the accelerator from a source spaced radially from said orbit, of means establishing a force acting radially on the electrons along substantially the entire periphery of said orbit prior to injection of the electrons, and means for diminishing said force rapidly with time at the instant of electron injection to thereby guide the injected electrons along a spiral path into said orbit.

2. The combination with an electron accelerator of the type wherein the electrons are caused to be accelerated along a stabilized circular orbit under the influence of a time varied magnetic field linking the orbital path of the electrons, and wherein the electrons are injected periodically from a source spaced radially from said orbit in timed relation with the variation in said magnetic field, of means actuated in timed relation with electron injection for producing a force acting radially on the electrons along substantially the entire periphery of said orbit, and means for diminishing said force with time simultaneously with the injection of said electrons to thereby guide the latter along a spiral path into said stabilized orbit.

3. An electron accelerator as defined in claim 2, and further including means actuated in timed relation with the main time varied magnetic field for reestablishing said radially acting guiding force upon completion of the acceleration of the electrons to thereby guide the electrons spirally away from the stabilized orbit.

4. A device for accelerating electrons as defined in claim 2 wherein said radially acting force for guiding the electrons is produced by an auxiliary magnetic field superimposed upon the main time varied magnetic field and which alters the normal gradient of the magnetic field to thereby shift the normal radius of the stabilized orbital

path of the electrons radially in the direction of the source of the electrons.

5. A device for accelerating electrons as defined in claim 4 and further including means thereafter operated in timed relation with said main magnetic field for reestablishing said auxiliary magnetic field upon completion of acceleration of the electron stream, the auxiliary field increasing rapidly with time to guide the stream spirally away from the acceleration orbit.

10 6. An electron accelerator as defined in claim 2 wherein the stabilized orbit lies in the air gap between juxtaposed annular poles, and the radially acting guiding force is constituted by an auxiliary magnetic field produced by a winding on at least one of said poles.

15 7. An electron accelerator as defined in claim 2 wherein the stabilized orbit lies in the air gap between juxtaposed annular poles, and the radially acting guide force is constituted by an auxiliary time varied magnetic field produced by a pair of windings, said windings being located outside and inside respectively of said annular poles.

20 8. An electron accelerator as defined in claim 2 wherein said radially acting guiding force is constituted by a radially directed electrostatic field set up between a pair of arcuate electrodes arranged parallel with and on opposite sides of the stabilized circular orbit.

25 9. A device for accelerating electrons as defined in claim 8 and further including control means operated in timed relation with said time varied magnetic field for subsequently reestablishing said electrostatic field to guide the accelerated electron stream away from the acceleration orbit.

30 10. A device for accelerating electrons as defined in claim 8 wherein the electrode located radially outward from the acceleration orbit is of smaller dimension in an axial direction than the radially inwardly located electrode.

35 11. A device for accelerating electrons as defined in claim 8 wherein said electrodes for establishing said electrostatic guiding field substantially enclose the acceleration orbit and are divided circumferentially into two electrode sets, one set covering between $\frac{1}{6}$ and $\frac{1}{3}$ of the path, and further including means operated in timed relation with the magnetic field for reestablishing an electrostatic field increasing with time between the latter set of electrodes upon completion of electron acceleration for guiding the electrons spirally away from the acceleration orbit.

40 12. A magnetic induction device for accelerating charged particles such as electrons to high velocity comprising, a magnetic field structure including a central core surrounded by a pair of juxtaposed annular poles, an evacuated annular tube located in the air gap between said annular poles, at least one magnetizing winding surrounding said control poles and central core, at least one auxiliary winding surrounding only said central core, means for cyclically energizing said windings to produce a time varied magnetic field in said central core and control poles, the magnetic flux produced in said central core by said auxiliary winding being opposed to the flux set up in such core by the other winding to establish a normal ratio between the flux in the central pole and the control poles by which a stabilized circular path of predetermined radius for electron acceleration is provided, means spaced radially from the stabilized acceleration path and operated in timed relation with energization of said magnetizing windings for injecting an electron stream into said tube, and means operated

45 50 55 60 65 70 75

in timed relation with electron injection to alter the normal counter-magnetizing effect of said auxiliary winding, said last means having a maximum effect at the instant of electron injection to effect a temporary radial shift of the stabilized acceleration path in the direction of the means for injecting the electron stream, which effect is thereafter diminished with time to establish a stabilized spiral path guiding the electron stream into the acceleration circle.

13. An electron accelerating device as defined in claim 12 wherein the means for altering the counter-magnetization effect of said auxiliary winding is comprised of a transformer whose secondary is connected in circuit with said auxiliary winding and whose primary is connected for energization in timed relation with electron injection.

14. The combination with a magnetic induction device for accelerating charged particles such as electrons along a stabilized circular orbit of predetermined radius in an evacuated chamber under the influence of a symmetrical time varied magnetic field linking the orbit and arranged perpendicularly thereto, in which the radius r of the stabilized orbit is determined in accordance with the equation

$$\phi = 2\pi r^2 H_r$$

where ϕ is the magnetic flux within the orbit and H_r the intensity of the field at the orbit, and in which the said electrons are periodically injected into said chamber in streams from an electron source spaced radially from the acceleration orbit in timed relation with the variation in said magnetic field, of means operated in timed relation with electron injection for guiding the stream along a spiral path into said acceleration orbit, said guiding means comprising a force acting radially upon the entering electron stream and which diminishes rapidly with time from the instant at which the electron stream is injected.

15. A magnetic induction device for accelerating charged particles such as electrons and the like to high velocity, comprising, an evacuated chamber providing an orbital path for electrons introduced therein, means adjacent said chamber for producing a main time varied magnetic field symmetrical with and perpendicular to the plane of said path, said field linking said path and having a gradient in the plane of the path such as to normally establish a stabilized circular orbit of predetermined radius along which the electrons are accelerated under the influence of said field, means spaced radially from said stabilized orbit and operated in timed relation with said main field producing means for injecting an electron stream into said chamber, and means operated in timed relation with electron injection for producing an auxiliary time varied field that is superimposed upon said main field to temporarily alter the normal gradient thereof, said auxiliary field being at its maximum value at the instant of electron injection to thereby shift the normal radius of the stabilized orbit in the direction of the initial path taken by the injected stream of electrons and thereafter diminished with time to establish a stabilized spiral path guiding the electron stream into said normal stabilized orbit upon restoration of said main field to its normal gradient.

16. A magnetic induction device as defined in claim 15 wherein the means producing said auxiliary time varied magnetic field is comprised of

a winding energized in advance of electron injection by a current having a predetermined direction through the winding and said auxiliary field is diminished by subsequent reenergization of said winding by a current of opposite direction.

17. A magnetic induction device as defined in claim 16 wherein the current for reenergizing the winding to diminish the auxiliary magnetic field is derived from a source of current connected to the winding through a grid controlled discharge valve, and the potential on the grid of said valve is controlled in timed relation with operation of said electron injection means to render said valve conductive simultaneously with injection of the electrons.

18. A magnetic induction device for accelerating charged particles such as electrons and the like to high velocity, comprising, an evacuated chamber providing an orbital path for electrons introduced therein, means adjacent said chamber for producing a time varied magnetic field symmetrical with and perpendicular to the plane of said path, said field linking said path and having a gradient in the plane of the path such as to normally establish a stabilized circular path of predetermined radius along which the electrons are accelerated under the influence of said field, means spaced radially from the stabilized acceleration path and operated in timed relation with the field producing means for injecting a stream of electrons into said chamber, a pair of electrodes arranged parallel with the acceleration path and disposed radially inward of and outward from said path, respectively, means operated in timed relation with electron injection for establishing a radially directed electrostatic field between said electrodes, said field being at a maximum at the instant of electron injection, and means for diminishing said field rapidly with time to thereby establish a stabilized spiral path for guiding the injected electron stream into the stabilized acceleration path.

19. A device for accelerating electrons as defined in claim 2 wherein said radially acting guiding force is constituted by a generally radially directed electrostatic field set up between a pair of arcuate electrode plates arranged parallel with and on opposite sides of the stabilized circular orbit, one of said plates extending for a greater distance than the other in the direction of the axis of the orbit to thereby introduce an axial component in the gradient of said electrostatic field.

20. A device for accelerating electrons as defined in claim 2 and further including an electric lens disposed adjacent the electron source for initially guiding the electron stream emitted therefrom.

21. A magnetic induction device for accelerating charged particles such as electrons to high energy levels comprising, a magnetic field structure including a central core surrounded by a pair of juxtaposed annular control poles, an evacuated annular tube located in the air gap between said control poles and which provides a circular orbit for said electrons, a magnetizing winding surrounding said control poles and core, means for energizing said winding to produce a time varied magnetic field in said core and control poles effecting acceleration of the electrons along said orbit, means for injecting electrons periodically from a source spaced radially from said orbit in timed relation with the variation

17

in said magnetic field, an auxiliary winding on said control poles energized with direct current for premagnetizing said control poles, and means actuated in timed relation with said electron injecting means for impressing an auxiliary time varied current on said auxiliary winding to produce a time varied magnetic field force acting radially on the electrons along substantially the entire periphery of said orbit, said force being diminished with time simultaneously with injection of the electrons thereby to guide the latter along a spiral path into said orbit.

22. A magnetic induction device as defined in claim 21 wherein the means for impressing the auxiliary time varied current on said auxiliary winding is comprised of a transformer, said transformer including a secondary winding connected in circuit with said auxiliary winding, a primary winding connected in circuit with said magnetizing winding and the means energizing

10

20

18

the same for compensating the potential induced in said auxiliary winding by the time varied field of said magnetizing winding, a second primary winding, and a source of time varied potential for energizing said second primary winding in timed relation with the operation of said electron injecting means.
